(57) **CLAIM**

The ornamental design of a pocket saver for a tape measure and the like, as described in the embodiments shown in the drawings.

DESCRIPTION

FIG. 1 is a front view of the pocket saver as shown in its environment, namely, fitting over the pocket and holding a tape measure or the like; the broken lines forming no part of the claim;

FIG. 2 is a perspective view of the pocket saver;

FIG. 3 is a bottom view of the pocket saver;

FIG. 4 is a back view of the pocket saver;

FIG. 5 is a side view of the pocket saver; and,

FIG. 6 is a top view of the pocket saver.
